United States Patent

Des. 238,205

Patented Dec. 23, 1975

238,205

PRINTING BAND

Robert M. Pabodie, Dayton, Ohio, assignor to Monarch
Marking Systems, Inc., Dayton, Ohio

Filed July 25, 1974, Ser. No. 491,911

Term of patent 14 years

Int. Cl. D18—99

U.S. Cl. D64—10

FIG. 1 is a perspective view of a printing band showing my new design;

FIG. 2 is an end elevational view of one end of the printing band shown in FIG. 1;

FIG. 3 is a side elevational view looking toward the left in FIG. 2;

FIG. 4 is an end elevational view of the opposite end of the printing band from that shown in FIG. 2; and

FIG. 5 is a side elevational view looking toward the left in FIG. 4.

I claim:

The ornamental design of a printing band, substantially as shown.
